J. R. PEIRCE.
GEOMETRICAL INSTRUMENT.
APPLICATION FILED AUG. 26, 1916.

1,242,467.

Patented Oct. 9, 1917.

UNITED STATES PATENT OFFICE.

JOHN R. PEIRCE, OF MONT CLARE, PENNSYLVANIA.

GEOMETRICAL INSTRUMENT.

1,242,467.

Specification of Letters Patent.

Patented Oct. 9, 1917.

Application filed August 26, 1916. Serial No. 117,057.

To all whom it may concern:

Be it known that I, JOHN R. PEIRCE, a citizen of the United States of America, residing at Mont Clare, in the county of 5 Montgomery and State of Pennsylvania, have invented new and useful Improvements in Geometrical Instruments, of which the following is a specification.

My present invention relates to an im- 10 proved geometrical instrument of that type employing a square and pivoted blade.

The primary object of the invention is to provide an instrument of this character especially adapted for use in beveling raft- 15 ers, joists, etc., and also adapted for use by draftsmen in laying off work.

The invention consists in certain novel combinations and arrangements of parts as will be hereinafter specified and claimed.

20 In the accompanying drawings I have illustrated one complete example of the physical embodiment of my invention constructed according to the best mode I have so far devised for the practical application 25 of the principles of my invention.

Figure 1 is a plan view of a complete instrument embodying the present invention.

Fig. 2 is an edge view of the instrument of Fig. 1.

30 Fig. 3 is an enlarged sectional view on line 3—3, Fig. 1.

Fig. 4 is an enlarged sectional view on line 4—4, Fig. 1, showing only the body of the instrument, the pivoted blade being 35 omitted for convenience of illustration.

In the preferred form of my invention as shown in the drawings, I have illustrated a square 1 which may be of wood, metal, celluloid, or any other suitable material, and 40 is provided with right angled edges 2 and 3. The square is provided with an additional pair of right angled edges 4 and 5, which are parallel with the edges 2 and 3, respectively so that a rectangular portion is pro- 45 vided in the square, with the edges 4 and 5 of precise and similar length. This formation provides for the extended angular portions 6 and 7 of the square, and of course these portions 6 and 7 are to be used for 50 the purpose of drawing perpendicular lines. The edges 4 and 5, of course, may also be used for drawing parallel or perpendicular

lines, but the special function of these edges 4 and 5 is to receive the scale indicated thereon which may be graduated in inches 55 and fractional parts as for instance on a scale of three inches to one foot, so that the numerals from one to eleven on the scales would indicate quarter inches.

The underside of the body 1 is recessed at 8 in order to provide for the free movement of the pivoted blade 9, which is provided with a pivot member 10 in the opening 10' of the square 1. The pivot blade is provided with a fixed screw or threaded pin 60 11, which is adapted to swing in an arcuate slot 12 which is struck from the pivot point 10 as a center, and by means of the thumb nut 13 the blade may be fixed in adjusted 65 position.

The outer edges of the body of the instrument are beveled, as is also the outer portion of the bevel 9, for convenience in use. The edge 9' of the blade, it will be noted, radiates from the center of the pivot 70 pin 10, and this edge is adapted to be used in conjunction with the graduated spaces on the two scales 4 and 5.

In use, if it is desired to secure a bevel 80 of nine inches to one quarter inch, the bevel 9 is moved to the position indicated in Fig. 1, and the blade is locked in its adjusted position by the use of the thumb nut 13, and the work may be properly laid out as desired.

85 From the above description taken in connection with my drawings, it will be seen that the device possesses efficiency, simplicity, and that it is comparatively inexpensive in first cost, and not liable to become disarranged, but may be manipulated with accuracy and despatch.

What I claim is:

1. A geometrical instrument of the square type comprising an integral body having a 90 pair of edges at right angles to each other, and a second pair of shorter edges arranged perpendicularly to these first mentioned edges, so that the edges of the first pair extend beyond the adjacent edges of the second, said second mentioned edges having scales thereon, and a blade pivoted to the body and coacting with said scales.

100 2. A geometrical instrument of the square

type having a pair of edges at right angles to each other, and a second pair of edges perpendicular to these first mentioned edges provided with scales, the body of the instrument being recessed at its underside, a blade pivoted in the body of the instrument and adapted to swing in the recessed portion,

said body having an arcuate slot, a threaded pin in the blade adapted to move in the slot, and a thumb nut on the pin adapted to hold 10 the blade in adjusted position.

In testimony whereof I affix my signature.

JOHN R. PEIRCE.
